UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

SHOE FORM

Application filed July 7, 1931. Serial No. 549,186.

This invention relates to an improvement in a shoe form more particularly in a form of the type comprising an expandible toe member and a back part wire, by the manipulation of which the toe member may be both inserted into the toe of a shoe and expanded therein to fall or plump out the toe material and also contracted in the toe and withdrawn therefrom in the contracted condition.

The primary object of this invention resides in the means for expanding or contracting the toe member, such means being a cross-brace of the toggle type having two sections, one end of one section being pivotally attached to one wall of the toe member and one end of the other section being pivotally attached to the other wall of the toe member, and the free ends of the sections being pivotally attached to the back part wire and to each other, certain of such attachments permitting a relative movement of the attached elements whereby the expansion or contraction of the toe member is performed in two stages, one stage by the making or breaking of the toggle formed by the crossbrace section and the other stage by the relative movement of the attached elements.

A further object of this invention resides in the provision of such a crossbrace wherein the means for attaching at least one section to a side wall includes a slot in the side wall and a button carried by the section and movable in the slot.

Another object of this invention resides in the provision of such a crossbrace wherein the means for attaching the ends of the sections to one another includes a slot in at least one section, whereby the sections are movable relative to each other and means normally preventing such movement.

Other objects of the invention will appear from a consideration of the following description of one embodiment of the invention and of the accompanying drawings in which such embodiment is shown and in which:

Fig. 1 is a side elevation of a shoe form embodying this invention;

Fig. 2 is a bottom plan view of a shoe form illustrating one embodiment of this invention showing the form in full lines after the com-

pletion of the first stage of the expansion or contraction movement and in dotted lines after the completion of the expansion movement;

Fig. 3 is a view similar to Fig. 2 of the shoe form after the completion of the contraction movement and in a position to be inserted into or withdrawn from the toe of a shoe;

Fig. 4 is a cross-sectional view taken along the line 4—4 on Fig. 2 illustrating one detail of that embodiment;

Fig. 5 is a bottom plan view similar to Fig. 2 of another embodiment of this invention;

Fig. 6 is a bottom plan view with parts broken away of a shoe form illustrating a third embodiment of this invention in the expanded condition;

Fig. 7 is a top plan view of the embodiment shown in Fig. 6; and

Fig. 8 is a bottom plan view of such embodiment in the partially contracted condition.

The shoe form selected to illustrate the invention comprises a toe member 10 and a back part wire 11. The wire 11 may be of such length that the loop 12 at the outer end thereof is adapted to contact with the heel counter of a shoe, as shown for example in my Patent 1,803,843, dated May 5, 1931, or may be shorter so that the loop will not contact with the heel counter. It will be understood that the term back part wire is of sufficient scope to include both types. The back part wire 11 may consist of a wire rod 13 enclosed within a tube 14 of celluloid or other material which may or may not be flexible.

The toe member 10 of the various embodiments comprises a hollow body portion 15 of celluloid or other flexible, resilient material having side walls 16, 17 which terminate in ball flanges 18 and 19 and are connected by a crossbrace 20 comprising sections 21, 22 pivotally joined at the inner ends as by a rivet 23. The embodiments of the invention differ in the form of crossbrace employed to connect the walls of the body portion 15.

In the embodiment shown in Figs. 2, 3 and 4 the outer end of the section 21 is pivotally attached to the flange 18 as by a rivet 24.

while the outer end of the section 22 is pivotally attached to the flange 19. It is desired that the outer end of the section 22 have a movement relative of the flange 19 in 5 addition to the pivotal movement. One means for insuring such movement is here shown as including an arcuate slot 25 which receives a button or pin 26 carried by the outer end of section 22. When the toggle is 10 made the sections 21 and 22 are in the position shown in Fig. 2, a tongue 27 being provided on the section 22 which engages one edge of the section 21 and limits the making of the toggle. The back part wire 11 is attached at its inner end to the crossbrace 23 by bending the inner end of the wire 13 around the shank of the rivet 23.

The form is inserted into the toe of a shoe in the entirely contracted condition shown in 20 Fig. 3 and the back part wire is advanced first to make the toggle, as shown in full lines in Fig. 2, thereby partially expanding the toe member and second to swing the cross brace 20 as a unit upon its pivot until the toe 25 has been plumped into the desired position. The amount of this second movement is determined by the material which forms the toe of the shoe and the crossbrace will not under ordinary conditions move to the limit indicated by dotted lines on Fig. 2. When the shoe form is removed from the shoe the back part wire 11 is retracted until the toe member has been contracted into substantially the condition shown in Fig. 3, so that it can 30 easily be withdrawn from the shoe.

The embodiment illustrated in Fig. 5 differs from that previously described in that the outer ends of both sections 21^a and 22^a of the crossbrace 20^a are attached to the ball 40 flanges of the body portion in the same way as is the section 22 attached to the flange 19. Thus both the flanges 18 and 19 are provided with arcuate slots 30 and 31 which receive 45 buttons 32 and 33 carried by the sections 21^a and 22^a respectively. The sections 21^a and 22^a are attached to the back part wire 11 and to each other by a rivet 23^a and the section 22^a is provided with a tongue 27^a which limits the making of the toggle by the advance 50 of the back part wire 11. It will be apparent that the crossbrace 20^a after the toggle has been made will advance as a unit guided by the slots 30 and 31 to expand the body portion of the toe member.

55 In the third embodiment (Figs. 6, 7 and 8) the crossbrace 20^b comprises sections 21^b and 22^b pivotally attached at their outer ends to the flanges 18 and 19 by studs or rivets 40 and 41 and attached to the back part wire 11 and to each other by a rivet 42. Through 60 the inner ends of the sections 21^b and 22^b extend slots 43 and 44 respectively, which receive the shank of the rivet 42 and thus permit movement of the sections relative to each 65 other. The outer ends of the sections are

formed with tips 45 and 46 respectively which bear against the walls of the toe member to limit the pivotal movement of the sections in one direction. (See Figs. 6 and 7). A length of spring wire 47 attached at its 70 ends to the side walls of the toe member, as for instance, to the studs or rivets 40 and 41, normally expands the form so that the sections are substantially in alignment, this expansion being limited by the engagement 75 of the rivet 42 with the outer ends of the slots 43 and 44.

The crossbrace sections 21^b and 22^b act, as do the sections in the other embodiment, as a toggle which is made either by the action 80 of the spring wire 47, when the toe member is free to expand, or by advancing of the back part wire, when the toe member is not free to expand, and is broken by retracting the back part wire, see Fig. 8. In this embodiment also the expansion or contraction of the toe member includes the movement of the crossbrace sections in two stages, one stage being the making of a toggle and the other stage being that movement of the sections 90 relative to each other permitted by the rivet 42 and slots 43 and 44.

When this embodiment is employed the toggle is first broken by retracting the back part wire 11 so that the toe member is partially contracted. The member is then inserted into the toe of the shoe, any further contraction required being provided by the relative movement of the sections against the urge of the spring wire 47. When within the 100 toe the spring 47 expands the member until the walls thereof bear against the material forming the toe. The back part wire is then advanced to make the toggle, the sections of the crossbrace moving relative to each other 105 against the urge of the spring wire as before unless, as practically never happens, the toe permits the toe member to assume the extreme expanded condition illustrated in Figs. 6 and 7.

While certain embodiments of the invention have been shown and described it will be understood that I am not limited thereto and that other embodiments may be made without departing from the spirit and scope 115 of the invention as set forth in the following claims.

I claim:

1. A shoe form comprising a toe member and a back part wire, said toe member comprising a hollow body portion, the side walls of which terminate in ball flanges and a crossbrace connecting such flanges, said crossbrace being made in two sections, the inner 120 ends of which are pivotally attached to each other and to the forward end of the back part wire member, and the outer ends of which are pivotally attached to the ball flanges, said sections, when in alignment, forming a toggle and certain of said attach- 125

ments permitting a relative movement of the attached elements, whereby the expansion or contraction of the toe member is performed in two stages, one stage by the making or 5 breaking of the toggle and the other stage by the relative movement.

2. A shoe form comprising a toe member and a back part wire, said toe member comprising a hollow body portion, the side walls 10 of which terminate in ball flanges, a crossbrace connecting said flanges made in two relatively movable sections and movable in two stages to expand or contract said toe member, primary means for moving the sections of the crossbrace in one stage and secondary means assisting the primary means for moving the crossbrace as a unit in the other stage.

3. A shoe form comprising a toe member 20 and a back part wire, said toe member comprising a hollow body portion, the side walls of which terminate in ball flanges, a crossbrace connecting said flanges made in two relatively movable sections and actuatable in two stages to expand or contract said toe member, means for moving the crossbrace in one stage by bringing the said sections substantially into alignment across the toe member, and means coacting with the first means 30 for moving the crossbrace in the other stage by moving the sections as a unit.

4. A shoe form comprising a toe member and a back part wire, said toe member comprising a hollow body portion, the side walls 35 of which terminate in ball flanges, a crossbrace connecting such flanges made in two relatively movable sections and actuatable in two stages to expand or contract said toe member, positively acting means for moving the crossbrace in one of said stages by bringing said sections substantially into alignment across the toe member, and means for moving the crossbrace in the other of said stages by 40 yieldably separating the sections, said means 45 acting independently of the first named means.

5. A shoe form including a toe member comprising a hollow body portion, the side walls of which terminate in ball flanges, a 50 crossbrace connecting such flanges and consisting of two sections, the outer end of each section being pivotally attached to a flange of the body portion, and the inner ends of the sections being pivotally attached so that the crossbrace functions as a toggle which is made when the sections are aligned to expand the body portion, and means for expanding said body portion, which means supplements the expanding action of the toggle.

6. A shoe form including a toe member comprising a hollow body portion, the side walls of which terminate in ball flanges, a crossbrace connecting such flanges and consisting of two sections, the outer end of each 60 section being pivotally attached to a flange of

the body portion, and the inner ends of the sections being pivotally attached so that the crossbrace functions as a toggle which is made when the sections are aligned to expand the body portion, and means for imparting movement to the crossbrace sections relative to the walls of the body portion of supplement the expanding action of the toggle. 70

7. A shoe form including a toe member 75 comprising a hollow body portion, the side walls of which terminate in ball flanges, a crossbrace connecting such flanges and consisting of two sections, the outer end of each section being pivotally attached to a flange of the body portion, and the inner ends of the sections being pivotally attached so that the crossbrace functions as a toggle which is made when the sections are aligned to expand the body portion, and means for making said toggle and for imparting to the brace sections a movement relative to the walls of the body portion to expand the toe member. 80

8. A shoe form including a toe member 85 comprising a hollow body portion, the walls of which terminate in ball flanges, and a crossbrace connecting said walls and made in two sections, the outer end of one section being pivotally secured to the flange of one wall, the flange of the other wall having an 90 arcuate slot therein, a stud carried by the outer end of the other section entering said slot, means pivotally connecting the inner ends of the sections, and a member pivotally attached to said means whereby the member 95 may be manipulated to bring the crossbrace sections into alignment and cause the crossbrace to shift as a unit guided by the slot in the flange.

9. A shoe form including a toe member 100 comprising a hollow body portion, the walls of which terminate in ball flanges, and a crossbrace connecting said walls and made in two sections, the outer end of each section being connected to a flange for movement 105 relative thereto, and the inner ends of the sections being pivotally connected so that the crossbrace functions as a toggle which is made when the sections are in alignment, one of said flanges having an arcuate slot and a 110 stud carried by the outer end of one section 115 and movable in the slot.

10. A shoe form including a toe member comprising a hollow body portion, the walls of which terminate in ball flanges, and a 120 crossbrace connecting said walls and made in two sections, the outer end of each section being connected to a flange for movement relative thereto, and the inner ends of the sections being pivotally connected so that the crossbrace functions as a toggle which is made when the sections are in alignment, one of said flanges having an arcuate slot and a stud carried by the outer end of one section 125 and movable in the slot, and a mem- 130

- ber for expanding the body portion of the toe member by making said toggle and moving said crossbrace relative to the body portion, such movement being guided by the travel of the stud in the slot.
11. A shoe form including a toe member comprising a hollow body portion, the walls of which terminate in ball flanges, a crossbrace connecting said walls and made in two sections pivotally joined at their inner ends and pivotally attached at their outer ends to the flanges, and spring means normally tending to expand the body portion and hold said crossbrace sections in alignment.
12. A shoe form including a toe member comprising a hollow body portion, the walls of which terminate in ball flanges, a crossbrace connecting said walls and made in two sections pivotally joined at their inner ends and pivotally attached at their outer ends to the flanges, and a spring wire connected at its ends to the side walls of the body portion and normally tending to expand the body portion and hold said crossbrace sections in alignment.
13. A shoe form including a toe member comprising a hollow body portion, the walls of which terminate in ball flanges, a crossbrace connecting said walls and made in two sections pivotally joined at their inner ends and pivotally attached at their outer ends to the flanges, studs by which the ends of the sections were attached to the flanges and a spring wire attached at its ends to the studs and normally tending to expand the body portion and hold said crossbrace sections in alignment.
14. A shoe form including a toe member comprising a hollow body portion, the walls of which terminate in ball flanges, a crossbrace connecting said walls and made in two sections pivotally joined at their inner ends and pivotally attached at their outer ends to the flanges, and spring means normally tending to expand the body portion and hold said crossbrace sections in alignment and a back part wire attached to the inner ends of such sections for drawing such sections out of alignment against the urge of said spring means.
15. A shoe form including a toe member comprising a hollow body portion, the walls of which terminate in ball flanges, a crossbrace connecting said walls and made in two sections, means pivotally attaching the outer ends of said sections to the flanges, the inner ends of the sections overlapping and each having a slot therein, a rivet extending through the slots to join the sections while permitting relative movement of the sections, and spring means normally tending to expand the body portion, to hold said crossbrace sections in alignment and to move such sections relative to each other.
16. A shoe form including a toe member comprising a hollow body portion, the walls of which terminate in ball flanges, a crossbrace connecting said walls and made in two sections, means pivotally attaching the outer ends of said sections to the flanges, the inner ends of the sections overlapping and each having a slot therein, a rivet extending through the slots to join the sections while permitting relative movement of the sections, and a spring wire connected at its ends to the side walls of the body portion and normally tending to expand the body portion, to hold said crossbrace sections in alignment and to move such sections relative to each other.
17. A shoe form including a toe member comprising a hollow body portion, the walls of which terminate in ball flanges, a crossbrace connecting said walls and made in two sections, means pivotally attaching the outer ends of said sections to the flanges, the inner ends of the sections overlapping and each having a slot therein, a rivet extending through the slots to join the sections while permitting relative movement of the sections, and a spring wire attached at its ends to the means by which the outer ends of the sections are pivotally attached to the flanges and normally tending to expand the body portion, to hold said crossbrace sections in alignment and to move such sections relative to each other.
18. A shoe form including a toe member comprising a hollow body portion, the walls of which terminate in ball flanges, a crossbrace connecting said walls and made in two sections, means pivotally attaching the outer ends of said sections to the flanges, the inner ends of the sections overlapping and each having a slot therein, a rivet extending through the slots to join the sections while permitting relative movement of the sections, and spring means normally tending to expand the body portion, to hold said crossbrace sections in alignment and to move such sections relative to each other, and a back part wire attached to said rivet for drawing the crossbrace sections out of alignment against the urge of said spring means.
19. A shoe form including a toe member comprising a hollow body portion, the walls of which terminate in ball flanges, a crossbrace connecting said walls and made in two sections, means attaching the outer ends of said sections to the flanges, the inner ends of the sections overlapping and each having a slot therein, a rivet extending through the slots to join the sections while permitting relative movement of the sections, and spring means normally tending to expand the body portion and move said cross brace sections relative to each other.
20. A shoe form including a toe member comprising a hollow body portion, the walls

- of which terminate in ball flanges, a cross brace connecting said walls and made in two sections, means attaching the outer ends of said sections to the flanges, the inner ends 5 of the sections overlapping and each having a slot therein, a rivet extending through the slots to join the sections while permitting relative movement of the sections, spring means normally tending to expand the body 10 portion and move said cross brace sections relative to each other, and a back part wire secured to said rivet.
